UNITED STATES PATENT OFFICE.

FRANK HORNQUIST, OF MOUNT JEWETT, PENNSYLVANIA.

BOLSTER AND AXLE ASSEMBLY FOR CHILDREN'S WAGONS.

Application filed July 2, 1923. Serial No. 649,117.

To all whom it may concern:

Be it known that I, FRANK HORNQUIST, a citizen of the United States, residing at Mount Jewett, in the county of McKean 5 and State of Pennsylvania, have invented certain new and useful Improvements in Bolster and Axle Assemblies for Children's Wagons; and I do declare the following to be a full, clear, and exact description of the 10 invention, such as will enable others skilled in the art to which it appertains to make and use the same.

My invention relates to improvements in children's wagons, such as coaster wagons, 15 and it is the principal object of the invention to provide a simple and inexpensive, yet a strong and durable bolster and axle assembly which does not require the use of a great number of bolts and does not necessitate that openings be formed through 20 either of the axles.

Another object is to provide a brace for the front hounds, held in engagement therewith by the pivot which connects the tongue 25 with the hounds.

With the foregoing in view, the invention resides in the novel subject matter herein-after described and claimed, the description being supplemented by the accompanying 30 drawings.

Figure 1 is a bottom plan view of a wagon embodying my invention.

Figure 2 is a longitudinal sectional view partly in elevation.

Figure 3 is a vertical transverse sectional view as indicated by line 3—3 of Fig. 2, showing the rear construction.

Figure 4 is a fragmentary disassembled perspective view of certain parts disclosed 40 in Fig. 3.

Figures 5 and 6 are vertical transverse sectional views of the front construction, as indicated by lines 5—5 and 6—6 of Fig. 2.

Figures 7 and 8 are detail vertical sectional views as indicated by lines 7—7 and 8—8 of Fig. 6.

Figure 9 is a detail horizontal section on line 9—9 of Fig. 6.

Figure 10 is a fragmentary perspective view of certain parts illustrated more particularly in Figs. 6 to 9.

Figure 11 is a detail sectional view showing a different form of construction including a cushioning spring.

Figure 12 is a horizontal sectional view 55 on line 12—12 of Fig. 11.

In the drawings above briefly described, the numeral 1 designates a body of a child's coaster wagon supported by a front axle 2, a rear axle 3, wheels 4, and front and rear 60 bolster structures of novel form.

The rear bolster, shown most clearly in Figs. 2, 3 and 4, includes an arched metal bar 5 having its crown secured by a bolt 6 to the body 1, the free ends 7 of the bar being disposed vertically. Each of these ends is formed with a circular opening 8 and with a vertically elongated slot 9 opening into the upper side of said opening. A transverse tie-bar 10 extends between the 70 ends 7 and is provided in its upper edge with vertically elongated notches 11 which receive the portions of the bar 5 at the upper ends of the slots 9, the portions of said tie-bar 10, under the notches 11, being snugly 75 received in the slots 9, so that said tie-bar is interlocked with the ends of the arched bar 5.

A pair of substantially U-shaped struts 12 are secured by bolts or other suitable 80 fasteners 13 to the body 1 and have slots 14 formed in their lower portions, through which the vertical ends 7 of the bar 5 pass, below the tie-bar 10. The slotted portions 85 of the struts 12 contact with the lower edge of the bar 10 and the lower surfaces of said slotted portion coincide with the walls of the openings 8, so that when the rear axle 3 is slipped through said openings, the bar ends 7, the ends of the tie-bar 10, and the 90 struts 12, will be held in interlocked relation without the use of fastening means other than the construction disclosed.

The front axle and bolster assembly is detailed more particularly in Figs. 2 and 5 95 to 10. This structure includes an arched bar 5^a having vertically elongated openings 8^a in its downturned ends 7^a and also having vertical slots 9^a which open into said openings 8^a. A horizontally disposed tie-bar 10^a is provided to prevent spreading of the ends of the bar 5^a and opposite edges of said bar 10^a are notched at their ends as indicated at 11^a to interlock with the upper portions of the metal at opposite sides of the openings 8^a. The slots 9^a permit the ends of the tie-bar 10^a to be inserted through the openings 8^a, after which said bar 10^a

may be turned to dispose it in a horizontal plane instead of a vertical plane, as was the case with the bar 10. The axle 2 is passed through the openings 8^a and contacts with the lower side of the tie-bar 10^b to hold the latter interlocked with the ends of the bar 5^a.

The center of the tie-bar 10^a is upwardly offset as indicated at 15 and a suitable strut 10 frame 16 rests upon said offset portion, the upper end of said frame 16 being secured by bolts 17 to the crown of the bar 5^a and to the lower plate 18 of a ball bearing whose upper plate 19 contacts with the body 1, balls 20 being disposed in suitable races between the two plates. A vertical king bolt 21 passes through the floor of the body 1, through the plates 18 and 19, through the lower end of the frame 16, and through the 20 upwardly offset center 15 of the tie-bar 10^a and thus pivotally connects the front structure with the body, as well as securing the lower end of the frame 16 to the tie-bar.

A pair of hounds 22 converge forwardly 25 from the ends of the axle 2 and have their front ends integrally connected by a U-shaped connecting portion 23 which is straddled by the fork 24 on the rear end of the tongue 25, said fork being pivoted to 30 the connecting portion 23 by a bolt or other suitable pivot 26. An inclined brace 27 is provided to hold the hounds 22 against vertical movement, the rear end of this brace having an opening through which the 35 king bolt 21 passes, while the front end of said brace is bent to form a hook 28 which snugly receives the front end of the connecting portion 23. To hold this hook and connecting portion in engagement with each 40 other, the pivot 26 passes across the front end of the brace 27 as disclosed clearly in Fig. 2.

In the preferred form of construction, the frame 16 is formed by bending a single 45 piece of strap iron, the terminals of this strap being disposed in abutting relation with opposite edges of the arm 27, as shown most clearly in Fig. 6.

Figures 11 and 12 disclose a construction 50 which may be used if springs are desired on the wagon. In these figures, 5^b designates an arched bar having downturned ends 7^b which are provided with vertical slots 8^b having parallel side walls. A tie-bar 10^b extends between the ends 7^b and is notched at 11^b to interlock with the portions 55 of said ends at the upper ends of the slots 8^b, said tie-bar being held in this position by substantially rectangular coiled springs 60 30 which surround the ends 7^b between said

bar 10^b and the axle 2^b, the ends of the axle being received in the slots 8^b, so that they may yield upwardly against the springs 30.

By employing the construction shown and described, or a substantial equivalent thereof, a child's wagon is provided which may be easily and inexpensively manufactured and will be exceptionally strong and durable. Most parts of the front and rear constructions, may be stamped from ordinary 70 strap iron or steel and easily bent to shape, which has numerous manufacturing advantages.

Excellent results are obtainable from the details disclosed and they may therefore be 75 considered as representing the preferred form of my invention, but it is to be understood that within the scope of the appended claims, numerous changes may be made.

I claim:

1. A wagon bolster comprising an arched metal bar, an axle engaged with the ends of said arched bar, and a tie-bar extending between the ends of said arched bar and held in engagement therewith by said axle. 80

2. A wagon bolster comprising an arched metal bar having openings in its ends, a tie bar having its ends passed through said openings and interlocked with the ends of said arched bar, and an axle passing 90 through said openings and retaining said tie bar interlocked with the ends of said arched bar.

3. A wagon bolster comprising an arched metal bar having openings in its ends, a 95 tie-bar having its ends received in said openings and provided with transverse notches snugly receiving portions of the first named bar ends contiguous to said openings, and an axle passing through said openings and holding said tie-bar in engagement with said first named bar ends.

4. A rear structure for children's wagons comprising an arched bolster having downwardly extending ends formed with openings and vertical slots opening into the upper edges thereof, a tie-bar having its ends inserted through said slots and formed with notches receiving the portions of the bolster at the upper ends of said slots, a 110 pair of U-shaped struts for the ends of said bolster having slots through which the ends of said bolster extend below the tie-bar, and an axle passed through said openings and confining said struts between itself and 115 said tie-bar.

In testimony whereof I have hereunto affixed my signature.

FRANK HORNQUIST.
